[57] CLAIM

The ornamental design for holder for cards or the like,
substantially as shown and described.

DESCRIPTION

FIG. 1 is a first embodiment of the front elevational
view of the holder for cards or the like showing my new
design;

FIG. 2 is a right side elevational view thereof;

FIG. 3 is a back elevational view thereof;

FIG. 4 is an enlarged top plan view thereof;

FIG. 5 is an enlarged bottom view thereof;

FIG. 6 is an enlarged cross sectional view taken along
line 6—6 of FIG. 1;

FIG. 7 is a front elevational view of the second embodi-
ment of the holder for cards or the like showing my new
design;

FIG. 8 is a right side elevational view thereof;

FIG. 9 is a back elevational view thereof;

FIG. 10 is an enlarged top plan view thereof;

FIG. 11 is an enlarged bottom view thereof;

FIG. 12 is an enlarged cross-sectional view taken along
line 12—12 of FIG. 7;

FIG. 13 is a front elevational view of the third embodi-
ment of the holder for cards or the like showing my new
design, the lower stem portion being removed, and
being identical to the stem of FIGS. 1—3 and FIGS. 7
—9; and

FIG. 14 is a right side elevational view thereof.
